UNITED STATES PATENT OFFICE.

A. C. RAND, OF NEW YORK, N. Y.

IMPROVEMENT IN MANUFACTURE OF ILLUMINATING-GAS.

Specification forming part of Letters Patent No. 88,982, dated April 13, 1869.

To all whom it may concern:

Be it known that I, ALONZO C. RAND, of the city, county, and State of New York, have made certain new and useful Improvements in Manufacturing Illuminating-Gas by decomposing crude petroleum or other hydrocarbon liquids; and I do hereby declare the following to be a full and exact description thereof, reference being had to the accompanying drawings, and to the letters of reference marked thereon.

The object of this invention is to decompose the vapors of crude petroleum, or other hydrocarbon liquids, by a fire or heat arranged automatically with reference to the quantity of gas in the gas-holder, thereby providing for the manufacture of a large quantity of gas in a small space, thus enabling dwellings and hotels in crowded cities to manufacture their own gas in a simple and effective manner.

In the drawings, A represents a still of peculiar construction, the vapor-pipe B being so arranged as to pass from the bottom of said still into the dome C, thus passing through the liquid in the still. D represents a cock attached to the bottom of said still, used to draw off any residue remaining therein. E represents a peculiar constructed gas-burner for distilling the liquid. F is the decomposer attached to the vapor-pipe B, and is also provided with a gas-burner, G, of peculiar or similar construction to E. H is a case surrounding the decomposer to retain the heat. I represents a condensing-worm connected with the decomposer used to condense any vapors that may not be fully decomposed.

The water-tank J is provided with a false bottom, so that the lower portion thereof forms an additional tank to hold the liquids that condense in said worm. This latter tank is provided with a draw-cock, K, and also a gas-outlet pipe, L, communicating with the interior of the gas-holder M. N is the gas-delivery pipe, provided at its lowest point with a drip-cock, O. Attached to the top side of the gas-holder is a projecting arm, P, connecting with a perpendicular rod, Q. The lower end of said rod is connected with the lever-handle to the gas-cock R, for the purpose of opening and closing the same, thereby regulating the amount or quantity of gas furnished to the burners E, thus regulating the heat. S represents the gas-delivery pipe leading to

the burners in the house. Connecting with this pipe S is the pipe T, furnishing gas to the still and decomposer.

The operation is extremely simple and effective, as will readily be noticed, self-operating or automatic. I will now proceed to describe the same. The still A is nearly filled with the liquid through the cap a, and the heat applied to the bottom of the still. The vapors arising from the heated oil pass upward into the dome C, thence downward through the vapor-pipe B, the lower portion of which is subjected to an intense heat, which partially decomposes them. From thence they pass into the decomposer F, which being supplied with a powerful heat they become thoroughly decomposed. The decomposer is so constructed that by unscrewing the nut on bolt b the cap or top of decomposer is easily removed, and any precipitate or dry carbon may be taken out. The gas-burners used to distil and decompose the vapors are so arranged that the gas is mixed with atmosphere before combustion takes place. The now thoroughly decomposed vapor passes through the cooling-worm I, and is delivered in the tank provided for the purpose of holding any vapors that may condense; from thence it passes, as before stated, into the gas-holder. When the gas-holder has attained a certain height, the quantity of gas furnished to the burners is lessened, and a consequent diminution of heat under the still, thereby lessening the amount of vapor furnished to the decomposer, and a consequent reduction of the quantity of gas delivered into the gas-holder. Thus it will be readily seen that this apparatus is entirely self-regulating, and a very small apparatus may be quite sufficient to light up the largest dwellings.

The movements of the gas-holder are never sufficiently great to entirely shut off the gas from the burner E. This is done by an extra cock provided for the purpose.

Having thus described my invention, what I claim as new, and desire to secure by Letters Patent, is—

The automatic method of regulating the fire under the still, substantially as set forth.

A. C. RAND.
